FIG. 1 is a perspective view of a hanging support for flower pots showing our new design;

FIG. 2 is a top plan view of FIG. 1;

FIG. 3 is a bottom plan view of FIG. 1;

FIG. 4 is a front elevational view of FIG. 1;

FIG. 5 is a side elevational view taken from the left of FIG. 1;

FIG. 6 is a perspective view of a second embodiment of the design of FIG. 1;

FIG. 7 is a top plan view of FIG. 6;

FIG. 8 is a bottom plan view of FIG. 6;

FIG. 9 is a front elevational view of FIG. 6;

FIG. 10 is a side elevational view taken from the left of FIG. 6;

FIG. 11 is a perspective view of a third embodiment of the design of FIG. 1;

FIG. 12 is a top plan view of FIG. 11;

FIG. 13 is a bottom plan view of FIG. 11;

FIG. 14 is a front elevational view of FIG. 11;

FIG. 15 is a side elevational view taken from the left of FIG. 11.

We claim:

The ornamental design for a hanging support for flower pots, as shown and described.
